US0D1021416S

(12) **United States Design Patent** (10) **Patent No.:** **US D1,021,416 S**
(45) **Date of Patent:** **** Apr. 9, 2024**

(54) **INTERDENTAL CLEANER**

(71) Applicant: **Esro AG**, Kilchberg (CH)

(72) Inventor: **Patrick Sutter**, Niederrohrdorf (CH)

(73) Assignee: **Esro AG**, Kilchberg (CH)

(**) Term: **15 Years**

(21) Appl. No.: **29/806,022**

(22) Filed: **Aug. 31, 2021**

(30) **Foreign Application Priority Data**

Mar. 2, 2021 (WO) WIPO102297

(51) **LOC (14) Cl.** **04-02**

(52) **U.S. Cl.**

USPC **D4/111**

(57) **CLAIM**

The ornamental design for an interdental cleaner, as shown and described.

DESCRIPTION

FIG. 1 is a perspective view of an interdental cleaner according to a first embodiment of the claimed design;

FIG. 2 is a front view thereof;

FIG. 3 is a back view thereof;

FIG. 4 is a left side view thereof;

FIG. 5 is a right side view thereof;

FIG. 6 is a plan view thereof;

FIG. 7 is a top view thereof;

FIG. 8 is a bottom view thereof;

FIG. 9 is a perspective view of an interdental cleaner according to a second embodiment of the claimed design;

FIG. 10 is a front view thereof;

FIG. 11 is a back view thereof;

FIG. 12 is a left side view thereof;

FIG. 13 is a right side view thereof;

FIG. 14 is a plan view thereof;

FIG. 15 is a top view thereof; and,

FIG. 16 is a bottom view thereof.

(Continued)

The broken lines shown in the drawings depict portions of the article, and form no part of the claimed design.

1 Claim, 8 Drawing Sheets
